DESIGN FOR A HOT WATER PLATE

Simon W. Farber, Brooklyn, N. Y.

Application January 18, 1940, Serial No. 89,559

Term of patent 14 years

To all whom it may concern:

Be it known that I, Simon W. Farber, a citizen of the United States, residing at Brooklyn, in the county of Kings and State of New York, have invented a new, original, and ornamental Design for a Hot Water Plate, of which the following is a specification, reference being had to the accompanying drawing, forming part thereof, wherein—

Figure 1 is a perspective view of a hot water plate showing my new design, and

Figure 2 is a side elevational view.

I claim:

The ornamental design for a hot water plate, substantially as shown.

SIMON W. FARBER.
